(57) CLAIM

The ornamental design for a garden basket, as shown and described.

DESCRIPTION

FIG. 1 is a perspective view of a garden basket according to our new design;

FIG. 2 is a front view thereof;

FIG. 3 is a rear view thereof;

FIG. 4 is a left, side view thereof;

FIG. 5 is a right, side view thereof;

FIG. 6 is a top plan view thereof; and,

FIG. 7 is a bottom plan view thereof.

Shading in the line drawings is included to convey the curvature and planes of the garden basket and not surface ornamentation.
